UNITED STATES PATENT OFFICE.

CHARLES F. YARDLEY, OF LARCHMONT, NEW YORK.

RAIL ANCHOR.

Application filed March 23, 1925. Serial No. 17,577.

To all whom it may concern:

Be it known that I, CHARLES F. YARDLEY, a citizen of the United States, residing at Larchmont, in the county of Westchester and State of New York, have invented certain new and useful Improvements in Rail Anchors, of which the following is a specification.

This invention relates to rail anchors or devices for preventing the creeping of railroad rails.

The objects of this invention are to provide a simple one-piece rail anchor, economical of manufacture and requiring a comparatively small amount of material, of great strength and rail-gripping tenacity, having a large tie-engaging area, and one which is easily applied to the rail, and easily removed therefrom when necessary.

It is one of the objects of my invention to provide a new and improved form and arrangement of parts in an anchor formed from a single piece of metal of substantially uniform cross-section, and substantially rigid, although capable of a limited spring action, by which the above named advantages may be attained.

The operation of the device, and the numerous objects and advantages of the invention will be better understood from the following detailed description of one approved form of rail anchor embodying the principles of this invention.

In the accompanying drawings; Fig. 1 is an elevation of the rail anchor in applied position, the positions of the anchor at two different stages in the process of applying same to the rail being indicated in dotted lines.

Fig. 2 is a plan view of the anchor in applied position.

Fig. 3 is a perspective view, on a smaller scale, of the anchor detached.

At 1 is indicated a standard rail, having a rail base comprising side flanges 2 and 3, the rail being secured to tie 4, with a tie plate 5^a interposed between the rail and the ties.

The rail anchor is formed of a single piece of metal of substantially uniform cross section from end to end thereof, this cross section being substantially square as here shown. The main body portion 5 of the anchor is normally straight, and one short end portion 6 is bent sharply upwardly and inwardly to form a short wedge-shaped or

V-shaped angle 7 with the body portion 5, the larger open end of this angle being only slightly greater than the thickness of the outer edge portion of flange 2 of the rail base. At its opposite end the anchor is bent upwardly and inwardly at an angle slightly less than a right angle, to form a rather long arm 8, which is provided near its inner upper edge with a notch or recess 9 adapted to engage over and grip the upper and lower edges of the rail base flange 3. The distance between the rail gripping portions of notch 7 and notch 9 is normally less than the width of the rail base, and the distance between the open end of notch 7 and the bend or angle 10, where the base of arm 8 joins with the body portion 5 of the anchor, is substantially equal to or slightly greater than the width of the rail base.

It will be noted that the anchor consists of a V-shaped metal member, having one long arm and one short arm, with a rail-flange-engaging notch near the inner extremity of each arm.

In applying the anchor to the rail, the arm 8 is first hooked about one flange of the rail, and with the edge of this flange as a pivotal axis the portion 6 of the anchor is swung up until the notch at the inner end thereof can be hooked about the opposite rail flange. Then with this latter rail edge as a pivotal axis the anchor is now swung down until the notch at the free extremity of the arm 8 is engaged with the first mentioned rail flange. Thus it will be seen that the process of applying the anchor involves two vertical swinging operations, first upwardly with one rail-flange as a pivot, and then downwardly with the opposite rail-flange as a pivot.

Describing this operation more in detail, the angle or shoulder 10 at the base of arm 8, is first applied to rail base flange 3, and the anchor is then swung about this flange 3 as a pivot, whereby the inner edge 11 of in-turned end 6 will just clear the lower edge of the opposite rail base flange 2. This position of the anchor is indicated by the dotted lines *a* in Fig. 1 of the drawing. As the anchor is swung further up, edge 11 of the in-turned end 6 will clear the upper edge of rail base flange 2, this position of the anchor being indicated by dotted lines *b* in Fig. 1. The anchor is now forced into position by driving the wedge shaped notch 7 onto flange 2 by striking the sharply bent

end portion 12 of the anchor with a spike maul at the point A, and by driving the arm 8 downwardly by means of a spike maul applied at the upper end of arm 8, as at B. 5 The anchor will spring sufficiently to allow the notch 9 to be sprung into engagement with the rail base flange 3. It will be seen from Figs. 1 and 2, that nearly all of one side face of body portion 5, as well as the greater part of one side of arm 8, will bear 10 against the side of the tie, thus giving a very large tie-engaging area in proportion to the size of the rail anchor.

Although this rail anchor when applied 15 will maintain a very tenacious grip upon the rail, it may be easily removed therefrom by blows of the spike maul applied to the upper end of arm 8, as at C, Fig. 1.

Although this anchor is very rugged and 20 strong, and of comparatively large cross section, it is of such simple construction that very little material is needed, and the anchor may be easily and quickly formed in a die by a few simple operations. The two simple 25 bends of the anchor are of large cross section, and are not sprung to any considerable extent when applied to the rail, so that the strength and the elasticity of the anchor are not seriously taxed.

30 I claim:

1. A rail anchor formed of a single bar of spring metal, with one end bent back to form a notch for engaging the upper and lower edges of one flange of the rail-base 35 with spring pressure, and the other end bent to form an upwardly extending arm having a rail base engaging recess near its upper end.

2. A rail anchor formed of a single bar 40 of spring metal, having a substantially straight body portion adapted to engage a tie, one short end bent sharply back to form a V-notch adapted to engage the upper and lower edges of one rail base flange, and 45 one long end bent up to form an arm having a rail base engaging recess near its upper end.

3. A rail anchor formed of a single bar of 50 spring metal comprising a substantially straight body portion adapted to engage the lower edge of one rail-base flange near one end, and having an inwardly and upwardly bent end-portion adapted to engage the upper edge of this rail-base flange, the opposite 55 end of the body portion being bent upwardly to form an arm having a rail base engaging recess near its upper end.

4. A rail anchor formed of a single bar of 60 spring metal comprising a substantially straight body portion adapted to engage the lower edge of one rail-base flange near one end, and having an inwardly and upwardly bent end-portion adapted to engage the up-

per edge of this rail-base flange, the opposite end of the body portion being bent upwardly to form an arm having a rail base engaging recess near its upper end, the distance between the rail base engaging portions being normally less than the width of the rail-base. 65

5. A rail anchor formed of a single bar of spring metal comprising a substantially straight body portion having a rail-base engaging notch at one end adapted to be distorted to grip the upper and lower edges of 70 one flange of said base, and an upwardly extending arm at the other end provided with a rail base-engaging notch. 75

6. A rail anchor formed of a single bar of spring metal comprising a substantially straight body portion having a rail-base engaging notch at one end for gripping the upper and lower edges of one flange of said base, and an upwardly extending arm at 80 the other end provided with a rail base-engaging notch, the distance between the rail base engaging notches being normally less than the width of the rail-base. 85

7. A rail anchor formed of a single piece of spring metal, comprising a substantially straight body portion, having an upwardly extending arm at one end provided with a rail base engaging notch near its upper end, and an inwardly bent end portion at the other end forming with the body portion a 90 wedge-shaped notch the open end of which is slightly larger than the thickness of the rail-base edge. 95

8. A rail anchor formed of a single piece of spring metal, comprising a substantially straight body portion, having an upwardly extending arm at one end provided with a rail base engaging notch near its upper end, and an inwardly bent end portion at the other end forming with the body portion a 100 wedge-shaped notch the open end of which is slightly larger than the thickness of the rail-base edge, the distance between the open 105 end of this notch and the base of the arm being substantially equal to the width of the rail base flange, and the distance between the two rail-base engaging notches being less than the width of the rail-base. 110

9. A rail anchor formed of a single metal member having a rail-flange engaging notch adjacent each of its ends for gripping the upper and lower edges of said rail flanges, the member being so proportioned that it may be applied to the rail by successive swinging movements, first about one rail flange to engage one notched end with the opposite rail flange, and then about the engaged flange to engage the other notched end with the first mentioned flange. 115 120
